UNITED STATES PATENT OFFICE.

EDWARD E. GOLD, OF NEW YORK, N. Y., ASSIGNOR TO GOLD CAR HEATING & LIGHTING COMPANY, OF NEW YORK, N. Y., A CORPORATION OF NEW YORK.

THERMOSTATIC MECHANISM.

1,077,224.

Specification of Letters Patent.

Patented Oct. 28, 1913.

Application filed December 10, 1909. Serial No. 532,369.

To all whom it may concern:

Be it known that I, EDWARD E. GOLD, a citizen of the United States, residing in the borough of Manhattan, city, county, and 5 State of New York, have invented certain new and useful Improvements in Thermostatic Mechanism, of which the following is a specification.

This invention aims to provide an improved 10 thermostatic mechanism of general application and which is specially useful in heating systems and apparatus for the steam heating of railway cars.

With this invention the system may be arranged 15 to work automatically as a pressure system, or to work automatically as a vapor system (at approximately atmospheric or lower pressure); being set at will and by a very simple operation to work according to 20 either principle as desired.

The apparatus is applicable also to other fields than the heating of railway cars; and contains features and combinations which are separately valuable as hereinafter 25 claimed.

The accompanying drawings illustrate an embodiment of the invention.

Figure 1 is a diagrammatic perspective of the system applied to the heating of a 30 railway car; Figs. 2 and 3 are horizontal sections of the controlling mechanism; Fig. 4 is a section approximately on the line 4—4 of Fig. 3; Fig. 5 is a vertical longitudinal section through the thermostatically controlled mechanism approximately on the line 35 5—5 Fig. 3.

Referring to the embodiment of the invention illustrated, A is the train-pipe carrying the supply of steam to the several cars. It is 40 provided beneath the floor B of the car with a pair of branches C, one running to each side of the car, and each connected by a vertical branch D passing through the floor of the car, and a horizontal branch E with the radiator F. A hand-operated stop-valve G is arranged within the car for use when the supply of steam is to be cut off entirely from the radiator. In the horizontal branch C below the floor of the car is an automatic admission 45 valve indicated as a whole by the letter H. This valve may be automatically controlled by thermostatic mechanism in a casing J, in which also is the discharge valve to which the discharging steam and water

of condensation are led through the inclined branch K within the car, the vertical branch L passing through the floor of the car and the horizontal branch M beneath the car. The controlling mechanism in the casing J is manipulated by means of a vertical shaft N passing upward through the floor of the car, and provided within the car with a handle N' by which it can be turned about 180 degrees. The handle N' for example may be located near or set down into the floor of the car and surrounded by a ring N², the handle carrying a pointer and the ring a pair of marks to indicate the pressure and no-pressure positions. When the handle is turned in one position the system operates under pressure. When the handle is turned in the opposite position the system operates as a vapor system.

Within the casing J of the regulating apparatus is a thermostat comprising, in this case, a vessel O of sheet metal carrying ether or other highly volatile liquid adapted to be vaporized and to expand the walls of the vessel when a sufficient temperature is applied thereto. The discharge valve P closes 75 against a seat Q which is fastened in one end of the casing J, and which is fastened also to the discharge pipe M of the radiator. The discharge valve P is provided with an extension R adapted to be 80 engaged by one of the flat walls of the thermostat and to transmit the movement of said wall to the valve. The valve tends normally to assume an open position under the expansion of a helicoidal spring S. The admission valve proper T is provided with a similar helicoidal spring U tending to hold the valve normally open. A stem V of the valve extends into the casing J and is provided there with a head W adapted to 85 engage the opposite flat face of the thermostat and to transmit the motion thereof to the valve. The stem V of the admission valve passes through the head of the valve casing, to which is connected by four tap-pet screws or in any other suitable way, a ring X having a spider or a set of arms Y connected with the casing J, so that the casing J of the regulating apparatus, the admission valve and its seat, and the discharge valve and its seat, are held together in a unitary structure which can be 95 readily applied upon existing systems by

merely intercalating the admission valve in the horizontal admission branch, and connecting the discharge pipe of the system with the opposite end of the casing J.

5 The conversion of the system from a pressure system to a vapor system or vice versa is effected by means of the vertical shaft N, the turning of which in one direction forces the member R against the corresponding face of the thermostat and holds it there (Fig. 3), while leaving the member W and the admission valve free to move under the expansion of the thermostat. The turning of the shaft in the opposite direction holds the part W fixed (Fig. 2) and leaves the part R free. In the first case the discharge valve is held fixedly open and the admission valve is opened or closed by the expansion or contraction of the thermostat 10 so as to regulate the quantity of steam admitted and, supposing the thermostatic liquid to be vaporized as soon as any steam passes through the discharge port, converting the system into one in which the quantity of steam admitted is limited to only such a quantity as will be condensed in the radiator and discharge pipes. In the second position (Fig. 2) the admission valve is held fixedly open and the discharge valve 15 is free, so that the system is converted into an ordinary pressure system in which when the steam escapes at the discharge there is an expansion of the thermostat and a closing of the discharge valve for a sufficient length of time to permit the accumulation of a small quantity of water of condensation, whereupon the cooling of the thermostat permits the discharge valve to reopen and discharge the water of condensation, 20 which is followed by steam which closes the valve again as before. The movements above described are transmitted from the reversing shaft N by means of an eccentric Z carried on the lower end thereof within 25 the casing. This eccentric actuates the head W of the admission valve spindle V directly, being arranged in a vertical opening through said head, and which opening is of a width slightly greater than the diameter of the eccentric. Thus when the eccentric is in the position of Fig. 2 it holds the admission valve wide open. When the eccentric is in the opposite position (Fig. 3) the admission valve is released, and by 30 reason of the play between the eccentric and the opening in the head W, the admission valve may be closed by the expansion of the thermostat. The discharge valve is controlled by similarly holding or releasing its head R. For this purpose an oblong ring a is arranged in a plane transverse to that of the thermostatic vessel O and surrounding the latter, and transmits the movement of the eccentric to the head R of the exhaust valve. At points in line with the axis 35

of the thermostat the ring a is divided so as to form smaller rings, b, c, at the opposite sides respectively, and which smaller rings are parallel with the thermostat. The ring b surrounds a flange on the head R of the discharge valve, so that when the ring a is shifted to the left it holds this head R stationary. The ring c passes about the head W and is provided with slots above and below the head W and in which the eccentric Z fits (Fig. 5). Now when the eccentrics are in the position of Fig. 2, besides holding the admission valve fixedly open, they release the head R from control by the ring a; and in the position of Fig. 3 the ring a is shifted to the left to bring the ring b against the flange of the head R so as to hold the discharge valve fixedly open, the admission valve being freed as previously explained. The horizontal ring a is supported at opposite sides upon lugs e on the side walls of the casing J.

For the purpose of rendering the operation of the trap more readily responsive to the conditions of the outside atmosphere, so that it will contract promptly after having been expanded to cut off the steam, the casing is arranged to induce a current of air in contact with the thermostatic vessel. The arrangement of the parts is similar to that shown in my Patent No. 507,268 of October 24, 1893, and others, relating to thermostatic steam traps. The discharge of the water of condensation and any escaping steam is by way of the valve P, whence the steam is conducted to the face of the thermostatic vessel and the water runs off through an opening f in the bottom of the casing. This same opening admits air for ventilation or quick cooling of the thermostat. The top and bottom of the casing are provided with lugs g which serve to hold the thermostat against displacement in a vertical plane. The bottom h of the casing is hinged at one side and provided with a link 110 and eccentric lock j at the opposite side, so that the casing may be readily opened for introduction and removal of the several parts. The inside line of the bottom h is shown in Figs. 2 and 3 passing between the opening f and the support for the foot of the reversing shaft N. The air which enters the opening f passes out at the upper part of the back of the casing through an opening k which is covered by a hood l containing a screen, the construction being similar to that employed in the well known Gold ventilating trap.

I make no claim in the present application to the complete heating system shown, the same being claimed in my application, No. 544,028, filed February 15, 1910.

What I claim is:—

1. A thermostatic mechanism including in combination a thermostat and a pair of

devices adapted to be actuated thereby, said thermostat being arranged to act on one of said devices and to react against the other simultaneously, and means for alternately holding said devices in positions to form reaction abutments for said thermostat.

2. A thermostatic mechanism including in combination a thermostat, and mechanism for alternatively providing different, substantially unyielding, reaction abutments for said thermostat, and for alternately utilizing the action of said thermostat in the directions opposite to the abutments.

3. A thermostatic mechanism including in combination a thermostat, a pair of bodily movable devices, means for pressing said devices yieldingly against opposite sides of said thermostat, and means for holding one of said devices against the thermostat and preventing its bodily movement, and leaving the other free to receive the expansive movement of the thermostat.

4. A thermostatic mechanism including in combination a thermostat, a motion-transmitting device at each side of said thermostat, and means for holding at will either of said devices fixed and leaving the other

free to transmit the movement of the thermostat.

5. A thermostatic mechanism including in combination a thermostat, a motion-transmitting device at each side of said thermostat, a ring passing about said thermostat and engaging one of said devices and a reversing means acting on said ring and the other of said devices to alternatively hold one of said devices fixed against the thermostat and leave the other free to transmit the movement of the thermostat.

6. A thermostatic mechanism including in combination a floating thermostatic vessel having opposite sides adapted to expand outward, and means for providing fixed abutments alternatively upon the opposite side faces of said vessel so as to cause the entire expansion to take place in the opposite direction.

In witness whereof, I have hereunto signed my name in the presence of two subscribing witnesses.

EDWARD E. GOLD.
